gineering Company, Philadelphia, Pa., a cor-
poration of Pennsylvania

Application January 14, 1936, Serial No. 59,043

13 Claims. (Cl. 110—44)

This invention relates to fluid control systems, and more particularly to systems employed to control the flow of draft air to stoker furnaces.

In stoker furnaces it is well known that for variable fuel burning rates, variable quantities of draft air must be supplied to effect efficient combustion of the fuel. For each change in fuel burning rate, as determined by the boiler requirements, a corresponding change in pressure of the air supplied to the fuel bed also takes place. The devices employed to control the flow of draft air to the fuel bed must therefore be capable of operating effectively throughout the range of operation of the furnace.

15 One object of the present invention is to provide a control system for furnace draft air which functions automatically to insure the proper flow of air to the fuel bed under all conditions of operation.

20 Another object is to provide a control damper for each furnace tuyère or group of tuyères which responds to the changes in the density of the fuel bed overlying the same, and to provide control means for such dampers which respond to the 25 changes in pressure at the source of air supply to maintain the dampers in balance throughout the range of operation of the furnace.

25 A more specific object is to provide a damper for each tuyère or group of tuyères which is op- 30 erated by the differential pressure created by the flow of air therethrough, and to provide an additional control therefor which is acted upon by the pressure in the plenum chamber so that the dampers will function at all times to permit the 35 proper amount of air to flow therethrough to the fuel bed.

Other and further objects will become apparent as the description of the invention progresses.

Of the drawings:

40 Fig. 1 is a longitudinal view partly in section taken through one of the tuyère chambers of a stoker, showing one form of air control mechanism, comprising the present invention.

45 Fig. 2 is an enlarged view partly in section taken through one of the tuyère chambers of the stoker showing the preferred air control system associated therewith.

Fig. 3 is an end view taken substantially along line 3—3 of Fig. 2.

50 Fig. 4 is a view partly in section of a valve forming a part of the control system shown in Figs. 1 and 2.

55 Fig. 5 is an enlarged view partly in section showing a modified form of control mechanism.

Fig. 6 is a view partly in section showing a further modified type of air control system.

Fig. 7 is a similar view disclosing a still further modification of the type of air control shown in Figs. 1 to 5.

Fig. 8 is a side elevational view partly in section of a stoker showing another embodiment of the present invention.

Fig. 9 is a side elevational view partly in section of the upper portion of a stoker showing a still 10 further embodiment of the present invention.

The present invention, for the purpose of illustration, is shown applied to a stoker of the underfeed type wherein the tuyères and communicating passages thereto constitute the ducts which 15 receive air from a common plenum chamber. The communicating passages to these tuyères are bounded on one side by movable dampers, while the other sides thereof are fixed. The static pressures operating against the inner sides of 20 these dampers are substantially the same as that of the air flowing through the associated tuyères providing, of course, that the areas of the passages and the associated tuyère openings are substantially the same. For a given rating the pressure of the fluid in the plenum chamber remains substantially constant, and since but little movement of the air occurs in this chamber, the total pressure therein is substantially static pressure. The dampers may be so disposed that the outer 25 sides thereof are subjected to the pressure of the fluid in the plenum chamber, or they may overlap so that a portion of the outer side of each forms a part or the whole of the upper wall of an adjacent communicating passage, and therefore is controlled, to a certain degree, by the static pressure of the air in said adjacent passage.

As is well known in the art, the combustion chamber disposed above the tuyères is maintained at a pressure materially lower than that of the plenum chamber, and accordingly the air flows through the tuyères in the direction of the combustion chamber. The rate of flow through the tuyères is determined largely by the resistance offered thereto created by the density of the fuel bed supported by the tuyères.

As the fuel bed decreases in density it is apparent that the rate of flow through the tuyères increases, and vice versa as the density of the fuel increases the rate of flow through the tuyères decreases.

Therefore, since one side of each damper is subjected substantially to the static pressure of the air flowing through the tuyères, while the other side thereof may be subjected wholly, or in part, to the total pressure of the air, it is seen 55

that when any flow exists past the dampers they are subjected to differential pressures. In actual practice the weights of the dampers are so proportioned as to counteract a predetermined differential pressure. In other words, the weight of each damper is so proportioned that it will remain open until the fuel bed overlying the associated tuyère becomes abnormally thin, at which time the differential pressure acting therein has increased to such an extent as to overcome this dead weight and as a result the damper will move to closed position, thereby shutting off the flow of air to the associated tuyère.

Now, in the event it is necessary to operate the furnace at a higher rating, which obviously requires a greater quantity of air to flow through the tuyères, the pressure of the air in the plenum chamber must necessarily be increased. Under these conditions it is seen that if the density of the fuel bed is substantially the same as it was while operating at the lower rating, then this increased pressure in the plenum chamber will cause an increase in the flow of air through the tuyères, subjecting the dampers to a greater differential pressure, and thus creating an unbalanced condition.

The present invention contemplates the provision of automatically operable compensating means for each of the dampers which retains the latter in balanced condition for each change in furnace rating so that the dampers will only close when the fuel bed over the associated tuyères becomes abnormally thin.

The accompanying drawings show several types of compensating devices for the dampers which may be utilized to maintain the same in balanced condition throughout the range of operation of the furnace, and each type will now be described in detail.

Referring to the drawings, numeral 1 designates a stoker of the underfeed type having alternately disposed retorts 2 and tuyère rows 3. Fuel is supplied to the retorts 2 from a hopper 4 and any suitable feeding device driven by a power mechanism indicated at 5, feeds the fuel gravitating in hopper 4 to the retorts 2. A series of pushers 6 mounted in the bottom of each retort 2 is also operated by the power mechanism 5 through the operating connections 7. These pushers underfeed the fuel along the retorts and tuyères to an extension grate 8, which in turn overfeeds the fuel to an ash pocket or dump plates (not shown) disposed at the rear of the stoker, in a well known manner.

It is to be understood that the invention herein described is not to be limited to its application to underfeed stokers, since it is equally adaptable for use in connection with other types of stokers, as well as other apparatus wherein fluid control is desired.

When the terms "front" and "rear" are hereinafter used in connection with the description of the elements of the stoker 1 and the associated fluid control, it will be understood that the portions of such parts extending toward the rear or extension grates 8 will be designated as "rear", and those portions thereof extending toward the front or driving mechanism 5, of the stoker will be designated as "front".

Referring more particularly to Figs. 1 to 3 inclusive, which illustrate the preferred embodiment of the present invention, each tuyère row 3 comprises a series of superimposed tuyère blocks 10, each having rounded rear portion 11, and a substantially rectangular front portion 12 ter-

minating in a flat tailpiece 13. Tuyères 10 may be of the general type shown and described in United States Patent No. 1,930,908, and rest upon the side plates 14 forming the side walls of the retorts and tuyère chambers respectively of the 5 stoker. As shown more particularly in Fig. 2, the tuyère blocks 10 in assembly are so constructed as to form a series of passages 15 therebetween through which the draft air from the plenum chamber 16 disposed beneath the stoker, flows to 10 the fuel bed supported thereby.

The control system illustrated in Figs. 1 to 3 of the drawings consists of a series of damper elements 18 pivotally mounted on pins 19, supported in the side walls 20 of a frame 21. Each of the 15 frames 21 in the present instance supports eight dampers, although they may be constructed so as to support any desired number without departing from the invention. Each frame 21 comprises a series of cross members 22 connecting the side 20 walls 20 thereof, and each frame is secured to the interior of the retort side walls 14 by any suitable securing means, such as by bolts 23. Each unit is placed beneath the tuyère blocks 10 in such a manner that the beveled forward portions 24 of 25 the tailpieces 13 thereof lie in substantially abutting relation with the upper surfaces of cross members 22, as shown in Fig. 2.

Each damper 18 consists of a substantially flat portion 25 extending between the side walls 20 of frame 21, and a vertically disposed substantially arcuate portion 26, which in assembly lies in substantially abutting relation with the vertically disposed substantially arcuate forward surface 27 of an associated cross member 22. Sufficient 30 clearance is provided between portion 26 of each damper and the corresponding arcuate surfaces 27 of cross members 22 to permit free movement of the dampers. The lower surfaces 28 of the cross members 22 are inclined and lie in substantially parallel relation with flat portions 25 of the dampers 18 and form therewith passages 29 communicating with the inlet passages 15 of the associated tuyères. The arcuate surfaces 27 of cross members 22 each terminate rearwardly of 40 the forward edges thereof forming ledges 30 upon which the lower end of the arcuate portions of the dampers rest when the latter are in fully open position, as shown in Fig. 2. By this construction it is seen that the upper surface of each 45 damper is subjected to the static pressure of the air flowing through its associated tuyère, while the lower surface thereof is at all times subjected to plenum chamber pressure. Therefore, when any flow exists in the passages 29 and 15 the associated dampers will be subjected to a differential 50 pressure.

For a fuel bed of uniform density throughout, it is believed to be apparent that this differential pressure will vary for each change in plenum 60 chamber pressure. At relatively low fuel burning rates when the pressure in the plenum chamber is maintained at an intensity equal, for example, to 2 inches of water, the differential pressure to which the dampers are subjected would be less than it would be if the fuel burning requirements change so as to require a plenum chamber pressure equal to 4 inches of water. Also, if this plenum chamber pressure were increased to 6 to 8 inches of water the differential pressures acting on the dampers would be correspondingly increased. Therefore, in order to permit the proper amount of air to flow past the dampers in accordance with the changes in fuel 70 75

burning rates, a compensating device 32 has been provided for each damper.

Each compensating device comprises a cylinder 33 having a piston 34 operating therein. The upper end of each piston 34 is operatively connected to an associated damper 18 by any suitable connection 35. Each cylinder 33 is connected to a pipe or duct 36 extending longitudinally of the tuyère chamber, which is closed at the lower end 37 thereof. The upper end of pipe 36 extends through the front wall of the stoker, and is connected to a pipe 36' extending transversely of the stoker, and to which the pipes 36 for the other tuyère chambers are also connected. A pipe 36'' is connected at one end to pipe 36', and at the other end to a chamber 38 subjected to an auxiliary source of pressure by means of any suitable fan mechanism 39. Pipe 36'' has mounted therein a three-way valve 40, provided with ports 43, 44 and 45, and a gate valve 41. As shown more particularly in Fig. 4, valve 40 may be actuated manually to different positions of adjustment by means of a handle 42. When handle 42 is in the full line position shown in Fig. 4, pipe 35 is connected to atmosphere through ports 43 and 44, and when said handle is moved to the dotted line position ports 44 and 45 will be in vertical alignment thereby establishing communication between chamber 38 and pipe 36'' while port 43 communicates with a relief valve 49. Relief valve 49 comprises an inlet port 49' and a discharge port 49''. A valve element 49''' held in closed position by a spring 49^{iv} normally prevents the escape of fluid through said valve. The pressure of spring 49^{iv} may be varied by an adjustable plug 49^v. By means of gate valve 41 the amount of fluid supplied to pipes 36 from chamber 38 may be varied. It therefore is seen that when valve 40 is adjusted to the position shown in Fig. 4, pipe 36'', and consequently pipes 36' and 36, will be connected to atmosphere, and thus the lower end 46 of each piston 34 is subjected to atmospheric pressure, while the upper surface 47 thereof is subjected to plenum chamber pressure. When valve 40 is in this position the force tending to hold each damper in open position not only consists of its own weight and the weight of the associated piston 34, but also of the additional force created by the plenum chamber pressure acting on the upper surface 47 of said piston. The force exerted upon the upper surface 47 of each piston obviously varies with the changes in plenum chamber pressure. Therefore, when the plenum chamber pressure reaches a maximum intensity the greatest force tending to hold the damper open will be exerted upon each of the dampers, and vice versa when the plenum chamber is of minimum intensity a minimum force will be imposed upon said dampers. The size and weight of each of the pistons 34 are so proportioned as to enable the associated damper to close when a predetermined differential pressure is imposed thereon. This predetermined differential pressure is determined by the resistance offered to the free flow of air through the associated tuyères for a fuel bed of a given density. For example, when the density of the fuel bed is reduced so that a bare spot would soon occur therein the differential in pressure acting upon the corresponding damper or dampers will be sufficiently great to cause the same to move upwardly to closed position, as indicated at 50 in Fig. 2. After the fuel feeding elements have built up that portion of the fuel bed to a greater density, the dampers will move downwardly to open position,

permitting air to again flow therethrough to the fuel bed.

Now let us assume that a greater fuel burning rate is required, and as a consequence thereof the plenum chamber pressure is correspondingly increased so as to cause a greater flow of air through each of the dampers. When this change occurs each damper will be acted upon by a greater difference in pressure but this will be counteracted by the action of the plenum chamber pressure upon the upper surface 47 of piston 34, and as a result the damper will remain open so long as the fuel bed remains normally uniform. However, should thin spots develop in the fuel bed over any of the tuyères the corresponding dampers will consequently be subjected to a still greater difference in pressure caused by the more rapid flow of air therethrough, and as a result the dampers will move to closed position to again shut off the air to those portions of the fuel bed.

It therefore is seen that the compensating devices 32 function to establish a balanced condition for the dampers due to each change in rating, and as a result the dampers will close only when thin spots occur over the associated tuyères.

It sometimes is desirable to subject the lower end 46 of each piston 34 to a pressure either above or below atmospheric pressure to effect balancing of the dampers. To this end the valves 40 and 41 are provided. When it is desired to operate the system in this manner lever 42 is swung to the dotted line position shown in Fig. 4, and gate valve 41 is so manipulated as to impose the desired pressure in pipes 36, and consequently in each of the cylinders 33. In order to determine the pressure to which the lower ends of pistons 34 are subjected, a manometer 51 is provided in pipe 36 adjacent control valves 40 and 41. Thus, by simply manipulating gate valve 41 the desired pressure may be imposed upon the lower ends of pistons 34. The tension of spring 49^{iv} acting on relief valve 49 is then adjusted by manipulation of plug 49^v so that said valve will open when the pressure in pipe 36 exceeds this predetermined pressure. When sufficient pressure has been introduced in pipe 36, gate valve 41 is fully closed. If the pressure in pipe 36 is less than that in plenum chamber 16, any leakage past the pistons 34 will tend to increase the pressure in said pipe. However, when this occurs relief valve 49 will open to exhaust to relieve pipe 36 of this additional pressure. When this pressure becomes normal again spring 49^{iv} will close the valve. In cases where the dampers 18 are unusually heavy it may be necessary to impose a pressure at the lower ends of pistons 34 greater than that in the plenum chamber. Under these conditions a non-flexible link connection is provided between the dampers and their associated pistons 34. When it is desired to impose a pressure at the lower ends of pistons 34 less than that of atmospheric pressure, fan 39 is so operated as to produce a partial vacuum in chamber 38, and consequently in pipes 36'', 36', 36 and cylinders 33.

It sometimes is desirable to have the dampers associated with each of the tuyères, overlay so that the conditions of the fuel bed which determine the flow through the various tuyères will control to a certain extent the operation of the adjacent dampers. To this end the construction shown in Fig. 5 has been provided. In this construction each damper 55 is provided with relatively flat upper and lower surfaces 56 and 57 respectively, which terminate at the rear ends thereof in a substantially arcuate portion 58. A

frame 59 in which these dampers are mounted is also provided with cross members 60 against which the forward ends of the tuyère blocks abut. The forward surface 61 of each cross member 60 is also of substantially arcuate construction corresponding to the curvature of portions 58 of the dampers 55. Each damper 55 has associated therewith a compensating device 32' similar in construction and operation to those shown in Figs. 1 to 3 of the drawings. In this construction, owing to the overlapping of the dampers, the pressure conditions of the air flowing past any of the dampers controls, to a certain degree the operation of the next adjacent dampers of the series. Due to this counteracting relationship between the adjacent dampers, each will remain at least partially open unless a comparatively great area of the fuel bed becomes abnormally thin. In other words, the lower surface of each damper is not entirely subjected to plenum chamber pressure, but rather, to a certain extent, to the pressure of the air flowing past the next lower damper so that the differential pressure to which it is subjected is somewhat reduced.

In the construction shown in Fig. 5 a somewhat different means is provided for introducing pressure to the lower ends of the pistons 34' operating in the cylinders 33' of the compensating devices 32'. As shown in Fig. 5, the pipe 36^a to which the cylinders 33' are connected, has provided therein a series of small apertures 62 through which fluid pressure from the plenum chamber 16' enters. The outer end of pipe 36^a may be connected to a pipe 36^b extending across the front of the stoker. A pipe 36^c depends from pipe 36^b and has provided therein a relief valve 63. A spring 64 normally retains the valve element 64' of said valve in seated position, and the pressure of said spring is adjusted by means of a plug 64'' making threaded contact with the lower end of the valve casing. A manometer 51' is also attached to the outer end of pipe 36^a adjacent valve 63, so that spring 64 may be so tensioned as to permit unseating of valve 63 when the predetermined pressure desired in pipe 36^a is exceeded. Plug 64'' may also be so adjusted that the valve will remain open. The lower ends of pistons 34' will then be subjected to atmospheric pressure. The type of dampers shown more particularly in Fig. 2 may be substituted for that shown in Fig. 5 without departing from the invention. In certain installations it may be desirable to control the air to a group of adjacent tuyères rather than to the individual tuyères, and to this end the construction shown in Fig. 6 has been provided. For the purpose of illustration, the tuyères 65 shown therein have been arranged in groups of four. Extending forwardly of each group of tuyères are partitions 66 and 67 respectively, which form an inlet passage 68 to each of such groups of tuyères. Partition 66 is substantially flat and terminates at the front end thereof in an arcuate portion 69, while partition 67 is of arcuate construction. The lower end of partition 67 is connected to a substantially flat portion 70 which joins at the forward end thereof the lower end of arcuate portion 69. A damper 71 is pivotally supported between the tuyère supports 72 and comprises substantially flat upper and lower surfaces 73 and 74 respectively, which terminate at their rearwardly disposed ends in a substantially vertical arcuate portion 75. Arcuate portion 75 lies in substantially abutting relation with the forward surface of arcuate portion 69, and when actuated to closed po-

sition, as shown in dotted lines in Fig. 6, engages the lower forwardly disposed end of partition 67. To prevent movement of the dampers 71 out of operative position a series of stops 76 are provided. A compensating device 77 is also provided for each damper 71. These compensating devices are similar in structure and operation to those shown in Fig. 2, and accordingly, a detailed description thereof is unnecessary. It therefore is seen, that when the differential in pressure acting on surfaces 73 and 74 of each damper is sufficient to overcome the dead weight thereof, and also the action of the piston provided in compensating devices 77, the damper will move to closed position. In this case also the operation of the dampers is effected only by changes in the density of the fuel bed overlying the associated groups of tuyères. The compensating devices in this construction also maintain the dampers in balanced condition for each change in furnace operation.

Fig. 7 shows a construction on the order of that shown in Fig. 6, but having a somewhat different damper arrangement provided therein. In this construction the tuyères 80 are also arranged in groups of four, each group having partitions 81 extending downwardly therefrom between the tuyère supporting plates 84. A damper 85 is pivoted at one end adjacent the lower end of partition 81, and rests upon a stop 86 when in its fully open position. Partitions 81 each have a forwardly extending projecting portion 87 which lies in substantially parallel relation with the dampers 85 when the latter are in fully open position, and forms therewith a throat 88 communicating with the passage 89 defined by partitions 81. In this construction a compensating device 90 is also provided for each damper 85. These compensating devices are similar in structure and operation to those shown in Figs. 1 and 2, and accordingly a detailed description thereof is unnecessary. The lower surface of each damper 85 is subjected to the pressure in the plenum chamber, while the upper surface thereof is subjected to the pressure of the air in passages 88 and 89, as determined by the fuel bed resistance over the associated group of tuyères. Therefore, when this differential pressure reaches a predetermined value caused by a diminishing in the fuel bed resistance, the damper will move upwardly toward closed position, as indicated by the dotted lines in Fig. 7, thereby shutting off the air supply to that portion of the fuel bed. When the fuel feeding elements build up that portion of the fuel bed, thereby creating a greater resistance to the flow of air, dampers 85 will again move to open position by the action of compensating device 90 and the dead weight of the damper itself, as previously described.

Fig. 8 shows a still further modification of the present invention. In this construction, like the previously discussed constructions, the tuyères 91 also abut at the forward ends thereof the cross bars 92 of a framework 93. A damper 94 pivotally supported at the sides thereof in framework 93 is provided with an arcuate member 95 which lies in substantially abutting relation with the forward vertically disposed substantially arcuate surface of an associated cross member 92. Each damper 94 is provided with a depending extension 96 terminating in an arcuate portion 97. Each arcuate portion 97 lies in operative relation with a nozzle 98 extending upwardly from a pipe 99. Pipe 99 is closed at

the lower end thereof, while its forward end extends through the front wall of the stoker and is connected to a communicating pipe 100. Pipe 100 extends across the front of the stoker, and has also connected thereto the pipes 99 for the other tuyère chambers of said stoker. A pipe 101 is connected to pipe 100 at one end thereof, the other end of which is connected to a constant pressure chamber 102. Pressure is supplied to pressure chamber 102 by any suitable fan 103 through a pipe 104. Mounted in a bracket 105 secured to the floor of the furnace room is a vertically disposed pressure regulator 106 of the bellows type. Pressure regulator 106 comprises a casing 107 having a movable plate 108 provided therein. The left hand side of plate 108 is connected to the pressure in plenum chamber 109 by means of a pipe 110. Plate 108 has secured thereto a guide rod 111 mounted for reciprocation in a bearing 112 provided in casing 107. Guide rod 111 is suitably connected to a valve rod 113 of an adjustable valve 114 provided in pipe 101 adjacent pressure regulator 106. A sliding valve element 115 is secured to the right hand end of valve rod 113, and is adapted to be moved toward closed position by the operation of diaphragm 108. Valve rod 113 has provided intermediate the ends thereof a stud 116 which engages into an extended slot 117 provided near the upper end of a lever 118. Lever 118 is pivoted intermediate its ends at 119 to a laterally extending bracket 120 secured to casing 107. A weight 121 is pivotally mounted at the lower end of lever 118.

In this construction the nozzles 98 supplied with variable amounts of fluid from chamber 102 through pipes 101 and 99, constitute the compensating device for dampers 94. Fig. 8 shows the parts in normal position at which time valve 114 is fully open, permitting a maximum amount of fluid to flow through pipes 101, 199 and 99 and be discharged through nozzles 98. As pointed out in connection with the description of the other embodiments of the present invention, when the stoker is operating at low ratings requiring a reduced plenum chamber pressure, the differential pressure acting on any of the dampers is relatively low. As the plenum chamber pressure increases, the differential pressure acting on the dampers increases correspondingly providing, of course, in each case the fuel bed remains normally uniform. Accordingly, in order to enable the dampers to function properly for the different ratings a compensating device must be provided. In this instance the dampers are so weighed that assistance is required to cause them to close, even when the fuel bed resistance is materially reduced when the stoker is operating at the lower ratings. When the parts are in the position shown in Fig. 8, the fluid pressure from chamber 102 is unrestricted, and consequently a maximum amount of air is directed against the arcuate portions 97 of the dampers 94. The pressure so derived, however, is not sufficient to cause the dampers to close; it merely compensates for the change in differential pressure due to operation of the furnace at a low rating. In the event the fuel bed should become abnormally thin over any of the tuyères, causing a greater flow of air therethrough, the increase in differential pressure created thereby, coupled with the assistance from the jets of air pressure from the associated nozzles 98, will be sufficient to cause closing of the dampers.

Now, as the fuel burning rate increases, causing an increase in plenum chamber pressure, plate 108 will move to the right a corresponding amount, thereby causing valve 115 to partially shut off the supply of fluid pressure to pipe 101. When this occurs a reduced force will be imparted to dampers 94 by the action of nozzles 98 to compensate for the difference in differential pressure to which the dampers are subjected by reason of this increase in plenum chamber pressure. When the stoker is operated at a maximum fuel burning capacity, plate 108 will have actuated valve 115 to fully closed position, thereby completely shutting off the air to nozzles 98 from the source of supply 102, and the dampers 94 will then be acted upon only by the differential in pressure created by the flow of air therethrough from plenum chamber 109. Plate 108 will be held in fully operated position against the action of weight 121, so long as the pressure in chamber 109 remains at this maximum value. Weight 121 obviously exerts a progressively greater counteracting force as lever 118 approaches a horizontal position due to the progressively greater moments of said weight. When the pressure in the plenum chamber decreases due to a lower fuel burning rate, weight 121 will actuate valve 115 toward open position a corresponding amount, and consequently a corresponding amount of fluid will be ejected from nozzles 98 against the portions 97 of dampers 94. This compensates for the reduction in the differential pressure acting upon the dampers caused by the reduction in plenum chamber pressure.

Fig. 9 shows a still further modification of the present invention. In this case also the tuyères 125 engage the cross members 126 of a frame 127 in which are mounted a series of dampers 128, one for each of the tuyères 125. Suspended from each damper 128 intermediate the ends thereof, is a weight 129. These weights are suspended by wires, rods or any other suitable means 130 which pass through eyelets 131 provided on a reciprocating rod 132. A downwardly extending arm 133 is secured to rod 132 which has provided at the lower end thereof a slot 134 which receives a pin 135 provided at the inner end of a second reciprocating rod 136. Rod 136 is guided for reciprocation in the front wall 137 of the stoker and in a guide bracket 138 extending downwardly from the front end 139 of the stoker. Extending forwardly from bracket 138 is a scale 140. Rod 136 has secured thereto near the right hand end thereof a pointer 141 disposed in operative relation with scale 140. Rod 136 has provided near the outer end thereof a block 142 having a pin 143 mounted therein which engages in a vertical slot 144 provided in the upper end of a lever 145. Lever 145 is pivoted intermediate its ends at 146 to a bracket 147 secured to and extending forwardly of a vertically disposed pressure regulator 148 and a weight 149 is pivotally mounted at the lower end of said lever. Pressure regulator 148 is of the bellows type having a movable plate 150 which is connected at the left hand side thereof to the plenum chamber 151 through a pipe 152. Plate 150 has secured thereto a guide rod 153 slidably supported in the casing of pressure regulator 148, and the outer end of said rod is pivoted at 154 to lever 145. By this arrangement it is seen that when the pressure in plenum chamber 151 increases, plate 150 will actuate the lever 145 in a counterclockwise direction about its pivot, causing

rods 136 and 132 to move to the left, and when the pressure reaches its maximum intensity lever 145 will have been moved to the dotted line position shown in Fig. 9. By this action each of the weights 129 will also be moved to the left, whereby the moments thereof are increased, and as a result the weights exert a greater downward force on the dampers 128. This increased force, tending to hold each damper open, compensates for the increase in differential pressure acting on the dampers due to the increase in plenum chamber pressure, tending to move them toward closed position. As the pressure in the plenum chamber 151 decreases weight 149 will tend to move rods 136 and 132 to the right, thereby reducing the moments of weights 129, and consequently reducing the downward force imposed on the dampers 128 to compensate for this reduction in differential pressure. When the furnace is operated at an extremely low rating the parts will assume the position shown in Fig. 1 wherein the weights 129 exert a reduced downward pressure on dampers 128. The dampers 128 thus remain balanced throughout the operating range of the furnace, and move to closed position only when the fuel bed overlying the associated tuyères becomes abnormally thin or porous.

In the event it is desired to adjust the weight 129 without the use of the pressure regulator 148, pin 143 is simply removed. Rod 136 may then be reciprocated manually from a knob 160 provided at the extreme right hand end thereof. Scale 140 is provided to enable proper manual adjustment of the weights 129.

While the embodiments herein described are admirably adapted to fulfill the objects primarily stated it is to be understood that the invention is not to be limited thereto since it may be embodied in other forms, all coming within the scope of the claims which follow.

What is claimed is:

1. In a device of the class described, the combination of a tuyère block adapted to receive fluid from a source of supply, means including a damper defining an air inlet passage to said tuyère block, one side of said damper being subjected to the pressure of the fluid in said passage, and the other side thereof being subjected to the pressure at said source of supply, whereby when said differential pressure exceeds a predetermined value said damper moves to closed position, and means controlled by the fluid pressure at said source of supply for further controlling the operation of said damper.

2. In a device of the class described, the combination of a series of tuyère blocks having passages therebetween adapted to receive fluid from a source of supply, a damper for each of said passages for controlling the flow of fluid therethrough, one side of each of said dampers being subjected to the pressure of the fluid in an associated passage and the other side thereof being subjected to the pressure at said source of supply, whereby when said differential pressure exceeds a predetermined value said damper moves to closed position, and a plurality of automatic means for controlling the operation of said dampers, one of said automatic means being provided for each of said dampers, each of said automatic means comprising a piston and a cylinder therefore, one end of said piston being subjected to the fluid pressure at said source of supply, and means for connecting the other end of said piston to another source of pressure.

3. In a device of the class described, the com-

bination of a series of tuyère blocks having passages therebetween adapted to receive fluid from a source of supply, a damper for each of said passages for controlling the flow of fluid therethrough, one side of each of said dampers being subjected to the pressure of the fluid in an associated passage and the other side thereof being subjected to the pressure at said source of supply, whereby when said differential pressure exceeds a predetermined value said dampers move to closed position, a plurality of automatic means for controlling the operation of said dampers, one of said automatic means being provided for each of said dampers, each of said automatic means comprising a piston and a cylinder therefore, one end of said piston being subjected to the fluid pressure at said source of supply, an auxiliary source of fluid pressure, means connecting the other end of said piston to said auxiliary source of pressure and valve means for controlling the pressure delivered to said pistons from said auxiliary source of pressure.

4. In a device of the class described, the combination of a tuyère block adapted to receive fluid from a source of supply, means defining an inlet passage to said tuyère block a damper mounted adjacent said passage for controlling the flow of fluid therein, one side of said damper being subjected to the pressure of the fluid in said passage, and the other side thereof being subjected to the pressure at said source of supply, whereby when said differential pressure exceeds a predetermined value said damper moves to closed position, and automatic means controlled by the fluid pressure at said source of supply for further controlling the operation of said damper.

5. In a device of the class described, the combination of a series of tuyère blocks, means forming passages between said tuyère blocks adapted to receive fluid from a source of supply, a damper for each of said passages for controlling the flow of fluid therethrough, one side of each of said dampers being subjected to the pressure in the associated passages, and the other side thereof partially overlapping the next lower damper of the series, thereby being subjected partially to the pressure in the next lower passage and partially to the pressure at said source of supply whereby, when said differential pressure exceeds a predetermined value said dampers will move toward closed position, and a plurality of automatic means, one for each of said dampers, actuated by the pressure at said source of supply for further controlling the operation of said dampers.

6. In a device of the class described, the combination of a series of tuyère blocks having passages therebetween adapted to receive fluid from a source of supply, a damper for each of said passages for controlling the flow of fluid therethrough, one side of each of said dampers being subjected to the pressure of the fluid in the associated passages, and the other side thereof being subjected to the fluid pressure at said source of supply, whereby when said differential pressure exceeds a predetermined value said dampers move toward closed position, and a plurality of automatic means for further controlling the operation of said dampers in accordance with changes in pressure at said source of supply, one of said automatic means being operatively connected to each of said dampers, each of said automatic means comprising a piston and a cylinder therefore, one end of said piston being subjected to the fluid pressure at said source of supply, means for connecting the other end of said pistons to pres-

sure delivered from said source of supply, and means for maintaining said last mentioned pressure at a predetermined value.

7. In a device of the class described, the combination of a series of tuyère blocks having passages therebetween adapted to receive fluid from a source of supply, a damper for each of said passages for controlling the flow of fluid therethrough, one side of each of said dampers being subjected to the pressure of the fluid in the associated passages, and the other side thereof being subjected to the fluid pressure at said source of supply, whereby when said differential pressure exceeds a predetermined value said dampers move toward closed position, and a plurality of automatic means for further controlling the operation of said dampers in accordance with changes in pressure at said source of supply, one of said automatic means being operatively connected to each of said dampers, each of said automatic means comprising a piston and a cylinder therefor, one end of said piston being subjected to the fluid pressure at said source of supply, means for connecting the other end of said pistons to pressure delivered from said source of supply, and an adjustable relief valve for maintaining said last mentioned pressure at a predetermined value.

8. In a device of the class described, the combination of a series of tuyère blocks having passages therebetween adapted to receive fluid from a source of supply, a damper for each of said passages for controlling the flow of fluid therethrough, one side of each of said dampers being subjected to the pressure of the fluid in an associated passage and the other side thereof being subjected to the pressure at said source of supply, whereby when said differential pressure exceeds a predetermined value said dampers move to closed position, a plurality of automatic means for controlling the operation of said dampers, one of said automatic means being provided for each of said dampers, each of said automatic means comprising a piston and a cylinder therefor, one end of each of said pistons being subjected to the fluid pressure at said source of supply, an auxiliary source of fluid pressure, means connecting the other end of said pistons to said auxiliary source of pressure, valve means for controlling the pressure delivered to said pistons from said auxiliary source of pressure, and an adjustable relief valve for maintaining constant the pressure supplied to said pistons from said last mentioned source of pressure.

9. In a device of the class described, the combination of a series of tuyère blocks adapted to receive fluid from a source of fluid supply, means including dampers defining passages between said source of fluid supply and said tuyère blocks, one side of each of said dampers being subjected to the pressure of the fluid in its associated passage, and the other side thereof being subjected, at least in part, to the pressure at said source of supply, whereby each of said dampers is subjected to a differential pressure, and means acting on each of said dampers and controlled by the fluid at said source of supply for controlling the operation of said dampers.

10. In a device of the class described, the combination of a series of tuyère blocks adapted to receive fluid from a source of supply, means defining inlet passages to said tuyère blocks, a normally open damper provided in each of said passages for controlling the flow of fluid therein, each of said dampers being so disposed that one side thereof is subjected to the pressure in its

passage, while the other side is subjected to the pressure at said source of supply, whereby when said differential pressure exceeds a predetermined value said damper moves to closed position, and means operating in response to the pressure at said source of supply for imposing an additional force upon said dampers.

11. In a device of the class described, the combination of a plurality of tuyère blocks having passages therebetween adapted to receive fluid from a source of supply, a plurality of dampers, one for each of said passages for controlling the flow of fluid thereto, one side of said dampers being subjected to the pressure of the fluid in said passages and the other side thereof being subjected to the fluid pressure at said source of supply, whereby when the differential pressure acting on any of said dampers exceeds a predetermined value it will move toward closed position, adjustable weight means for each of said dampers tending to hold the same in open position, automatic means for varying the moments of said weights in accordance with the changes in fluid pressure at said source of supply to counteract the changes in differential pressure acting on said dampers caused by the changes in pressure at said source of supply, said automatic means comprising reciprocable means operatively connected to said weights, and a pressure regulator connected to said reciprocable means and operable in one direction by the fluid pressure at said source of supply, and weight means counteracting the operation of said pressure regulator for actuating said reciprocable means and first mentioned weights in the reverse direction when the pressure at said source of supply decreases.

12. In a device of the class described, the combination of a plurality of tuyère blocks, having passages therebetween adapted to receive fluid from a source of supply, a plurality of dampers, one for each of said passages for controlling the flow of fluid thereto, one side of said dampers being subjected to the pressure of the fluid in said passages and the other side thereof being subjected to the fluid pressure at said source of supply, whereby when the differential pressure acting on any of said dampers exceeds a predetermined value it will move toward closed position, adjustable weight means for each of said dampers tending to hold the same in open position, manual means for varying the moments of said weights in accordance with the changes in fluid pressure at said source of supply to counteract the changes in differential pressure acting on said dampers caused by the changes in pressure at said source of supply, said manual means comprising reciprocable means operatively connected to said weights, and indicator means whereby the extent of movement of said reciprocable members and weights may be determined.

13. In a device of the class described, the combination of a plurality of tuyère blocks, having passages therebetween adapted to receive fluid from a source of supply, a plurality of dampers, one for each of said passages for controlling the flow of fluid thereto, one side of said dampers being subjected to the pressure of the fluid in said passages and the other side thereof being subjected to the fluid pressure at said source of supply, whereby when the differential pressure acting on any of said dampers exceeds a predetermined value it will move toward closed position, adjustable weight means for each of said dampers tending to hold the same in open position, automatic means for varying the moments

of said weights in accordance with the changes in fluid pressure at said source of supply to counteract the changes in differential pressure acting on said dampers caused by the changes in pressure at said source of supply, said automatic means comprising reciprocable means operatively connected to said weights, a pressure regulator connected to said reciprocable means and operable in one direction by the fluid pressure at said source of supply, and weight means counteracting the operation of said pressure regu-

lator for actuating said reciprocable means and first mentioned weights in the reverse direction when the pressure at said source of supply decreases, means for disconnecting said pressure regulator from said reciprocable means to permit manual adjustment thereof, and indicator means whereby the extent of movement of said reciprocable means and weights may be determined.
